EX

Pat. 1.517.

Improvement in light rotundos
By John D. Howland, of New Haven, Conn.
Edwin S. Howland, Son of John D. Howland, Conn.
Jenny W. Howland, Nov. 1, 1862. Patented Jan'y. 21. 1862.

UNITED STATES PATENT OFFICE.

STEPHEN D. ARNOLD, OF NEW BRITAIN, CONNECTICUT, ASSIGNOR TO P.
AND F. CORBIN, OF SAME PLACE.

DESIGN FOR A LIFT OR HANDLE.

Specification forming part of Design No. 1,517, dated January 21, 1862.

To all whom it may concern:

Be it known that I, STEPHEN D. ARNOLD, of New Britain, county of Hartford, and State of Connecticut, have invented or produced a new and original Design or Pattern for a Lift or Handle; and I do hereby declare that the following is a full and exact description of the same.

In the accompanying drawing is shown my improvement.

a represents a handle as if formed of a twisted cord, and bent into the desired shape therefor. *c* represents a pendant as if formed of twisted cord. The handle and pendant combined produce a new, rich, and highly-ornamented

design or pattern for a lift or handle, substantially as shown and described.

What I claim, therefore, and desire to secure by Letters Patent, is—

The design or pattern for a handle, viz: the combination of the handle *a* with a pendant, *c*, to produce a rich and highly-ornamental design or pattern for a lift or handle, substantially as and for the purpose represented and described.

STEPHEN D. ARNOLD. [L. S.]
